UNITED STATES PATENT OFFICE.

MYRTLE E. SMITH, OF GLENWOOD, WASHINGTON,

CAP.

Application filed November 11, 1925. Serial No. 68,386.

This invention relates to improvements in headwear and has especial relation to caps, an object being to provide an ornamental cap by means of which the hair of the 5 wearer may be prevented from becoming disarranged, the cap being especially designed for use when riding in an automobile.

Another object of the invention is the provision of a cap of novel construction which 10 includes a crown of open formation, novel means being provided for securing the crown to the head band of the cap and for securing the crown forming members together, to 15 provide a crown of ornamental and attractive design.

With the above and other objects in view, the invention further includes the following novel features and details of construction, to be hereinafter more fully described, 20 illustrated in the accompanying drawings and pointed out in the appended claim.

In the drawings:—

Figure 1 is a view illustrating the cap in 25 use.

Figure 2 is an enlarged detail view of one of the connecting beads.

Figure 3 is a fragmentary view illustrating 30 the manner of forming the crown of the cap.

Referring to the drawings in detail wherein like characters of reference denote corresponding parts, the cap which is preferably made of bead work comprises a head band 35 10. This band may be of any desired character or design, it being preferred to arrange the beads of which it is formed, so as to provide an ornamental design such as illustrated in Figure 1 of the drawings. The 40 construction of the band includes an upper marginal cord or wire 11 to which are con-

nected a number of crown wires or threads 12. These wires or threads 12 are also designed to hold beads 13 and may be arranged in various forms. For this purpose, 45 the invention provides metallic beads 14 which are transversely split as indicated at 15, one of these beads being illustrated in Figure 2 of the drawings. The splits of the beads are substantially V-shaped and their 50 ends abut substantially flush so as to reduce danger of entangling the wearer's hair. The beads 14 are also utilized for connecting the threads or wires 12 to the band 10, the threads or wires being passed through the 55 slit portion of the beads 14 and the slit thereafter closed. The threads or wires 12 may thus be connected at desired points around the edge of the head band 10, while the said threads or wires 12 may also be 60 connected to one another so as to form various ornamental designs such as illustrated in Figure 1 of the drawings.

The invention is susceptible of various 65 changes in its form, proportions and minor details of construction and the right is herein reserved to make such changes as properly fall within the scope of the appended claim.

Having described the invention what is 70 claimed is:—

A head covering comprising a head encircling beaded band having a marginal thread, a plurality of crown threads, beads upon the crown threads and split bendable 75 beads connecting the crown threads to the thread of the band and to one another to provide an ornamental crown, the splits of said beads being substantially V-shaped with their ends abutting.
